UNITED STATES PATENT OFFICE.

JOSEPH WILLIAM MÜLLER, OF FOREST, WASHINGTON.

COW-TIE LOCK.

1,084,705.

Specification of Letters Patent.

Patented Jan. 20, 1914.

Application filed April 15, 1912. Serial No. 690,928.

To all whom it may concern:

Be it known that I, JOSEPH W. MÜLLER, a citizen of the United States, residing at Forest, in the county of Lewis, State of Washington, have invented certain new and useful Improvements in Cow-Tie Locks; and I do hereby declare the following to be a full, clear, and exact description of the invention, such as will enable others skilled in the art to which it appertains to make and use the same.

This invention relates to locks.

The primary object of the invention is to provide a device of this character adapted to be employed in connection with a halter, or to connect two chains for securing a cow or other animal within its manger or stall so as to permit the animal to be readily turned loose as for instance, in case of fire.

Another and important object of the invention is to provide a simple, novel and improved form of lock for use in connection with a chain, halter or other tying device having one section permanently connected to the lock while the other section is removably secured thereto.

With the above and other objects in view, the invention consists of certain other combinations and arrangements of parts as will be hereinafter more fully described, claimed and illustrated in the accompanying drawings, in which:

Figure 1 is an enlarged longitudinal sectional view of the lock and portions of a chain halter connected therewith, the shackle of the lock being in a closed position. Fig. 2 is a similar view but showing the shackle released from the bolt of the lock for disconnecting an end of the tie loop. Fig. 3 is a plan view of the lock. Fig. 4 is a cross sectional view on the line 6—6 of Fig. 1.

My improved lock is illustrated in connection with chain sections, indicated by the numerals 14 and 16.

The lock comprises a main bar or flat body member 19 which is bifurcated at one end to form a pair of spaced apertured ears 20 between which one extremity of a bow-shaped shackle 21 is pivoted upon a pin 22 and has its notched free end movable toward and away from the opposite extremity of the bar in moving to a locked or unlocked position. Connected to the bar 19 is the lock casing which comprises the side plates 23 which are riveted to the bar as shown at 24.

The edge portions of the casing are closed

by a flat strip of metal 25 which is secured to the bar 19, as shown at 26, and is also formed with a bearing 27, for securing the free extremity of the chain section 14 to the 60 leek through the medium of a clevis or loop 28 which has the extremities of its leg portions engaged upon opposite sides of the bearing, and is detachably and pivotally connected thereto by means of a removable 65 pin 29 retained in position by a key 30. The edge strip 25 is bent in substantially U-form so that its bight portion 31 is spaced from the adjacent ends of the bar and plates while the top portion 32 of the strip is bent inwardly at right angles at its forward end and the extremities of the strip are riveted to the bar by a common fastening member 33, said right angularly bent portion forming the inner end 34 of the casing. 75

The casing is provided with a central longitudinal slot 35 while mounted within the casing is a spring-actuated hollow catch member 36, the same comprising a single strip of sheet metal bent at right angles at 80 three points to form a substantially U-shaped member having a forward finger-engaging end or leg 37 communicating with the space inclosed by the bight portion of the edge strip, while the inner end or leg 38 85 extends in the direction of said bight portion and extends across the slot 35, as shown at 39. The catch member 36 is held in its normal operative position by means of a coiled expansion spring 40 disposed between 90 the inner end of the bolt and the inner end wall of the casing, whereby the curved free end of the shackle may be moved into the slot for automatically engaging the inner end of the portion 39 with a notch 41 in said 95 end of the shackle while said free end of the shackle extends into the hollow catch member. In this operation of engaging the shackle with the bolt, the spring 40 will give sufficiently to allow the inclined end of the shackle to ride over the end of the portion 39, and the spring will then force said end into the notch for securely holding one of the circular links 17 between the shackle and the bar at their pivoted ends. By slight 100 pressure against the engaging portion 37 forward end of the portion 39 is disengaged from the notch 41, thereby freeing the shackle so that a slight pull upon the chain section 16 will open the loop. The bight 105 portion of the edge strip of the casing prevents accidental depression of the bolt, but

such depression can be readily accomplished by manual application of force properly directed by placing a finger within the loop or bight portion and pressing against the element 27. A transverse pin 42 is carried by the casing to limit the movement of the clutch member 36.

It will be seen that I have provided a device of this character which is fully capable 10 of attaining the foregoing objects, in a thoroughly practical and effective manner.

I do not limit my invention to the exact 15 details of construction, combination and arrangement of parts, as herewith illustrated and described, but my invention may only be limited by a reasonable interpretation of the claim.

I claim:—

20 In a lock, a body member, a hollow casing secured to the body member and provided

with a loop and with a longitudinal slot, a hollow catch member slideable within the casing and having an element extending across said slot, means for holding the hollow catch member normally with its lower side 25 exposed within the inclosure of said loop, said catch member being protected against accidental displacement by said loop and adapted to be moved by a finger of a person extending into the loop, and a shackle pivotally connected to the body member and adapted to be swung into such position that its free end extends into the hollow catch member and engages therewith.

30 In testimony whereof, I affix my signature, in presence of two witnesses.

JOSEPH WILLIAM MÜLLER.
